UNITED STATES PATENT OFFICE.

SAMUEL B. SHELDON, OF BUFFALO, NEW YORK.

PROCESS FOR COOKING COAL.

959,026.

Specification of Letters Patent. Patented May 24, 1910.

Application filed August 5, 1906. Serial No. 447,026.

To all whom it may concern:

Be it known that I, SAMUEL B. SHELDON, a citizen of the United States, of the city of Buffalo, in the county of Erie and State 5 of New York, have invented certain new and useful Improvements in Processes of Coking Coal; and I do hereby declare that the following is a full, clear, and exact description thereof, reference being had to the 10 accompanying drawings, and to the letters of reference marked thereon, which form a part of this specification.

This invention relates to improvements in the art of distilling coal for the manufacture 15 of coke and the production of gas and more especially to improvements in the process of effecting the coking or distillation of coal and at the same time saving the gas produced in the operation.

20 The process constituting my present invention embraces generally the steps of introducing the coal to be coked into an inclosure, conducting into contact with the walls of said inclosure, to effect the coking 25 or partial coking of the coal, the heated gaseous products of combustion from fuel burned in connection with air heated by a regenerator, and transmitting to the coal, before its introduction into the inclosure, 30 non-coking heat derived from a portion of said products of combustion not needed for heating the regenerator, to effect a preliminary heating of said coal.

My invention may be better understood 35 by reference to the accompanying drawings in which are illustrated two forms of coking apparatus adapted for carrying my novel process into practice.

In the drawings:—Figure 1 is a longitudinal vertical section taken through the heating flues of a coking oven, and showing, in vertical section, a preheating chamber and a supply bin; this figure illustrating means for heating a supply bin by the use 40 of products of combustion taken from the heating passages of the coking oven after the same have been utilized to effect the preheating or superficial coking of the coal. Fig. 2 is a perspective view of a series of 45 "Otto Hoffman" ovens together with supply bins for said ovens, and means for heating the walls of said supply bins by heated products of combustion derived 50 from the flues or heating passages of said ovens, one of said ovens being shown in vertical section taken through the up-

right heating flues in the wall between two of the coking chambers.

In Fig. 1 I have shown an apparatus for carrying out my novel process, embracing a 60 preheating passage in which the coal is compressed and superficially coked and a supply bin which is preliminarily heated by products of combustion taken from the heating flues of the coking oven. In this apparatus, the said heated products of combustion, on their way from the coking oven to the supply bin, are utilized to effect the superficial coking of the coal in the said 65 coking passage. As shown in said Fig. 1, a 70 receiving chamber 2, a tapered coal compressing passage 3, a preheating passage 4, a jacket 5, forming a combustion chamber 6, and a reciprocating plunger 7 in the receiving chamber, are made in the same manner 75 as in my prior Patent No. 855,069. An open-topped supply bin 8 is connected at its lower end with the admission opening of the receiving chamber 2 and is surrounded by a jacket 9. A pipe 10 connects the top of 80 the combustion chamber 6 with the lower end of said jacket 9, and the upper part of said jacket is provided with an exit pipe 11 which leads to a horizontal transverse flue 12, connected by a pipe 13 with a stack 14. 85 The coking oven illustrated in said Fig. 1 is a double "Otto Hoffman" oven such as is shown in my said prior Patent No. 855,069; the oven being shown in vertical, longitudinal section, taken through the flues or passages in the partition wall between two of the coking chambers of the oven. In said figure, 15, 16 indicate the lower, horizontal, 90 passages in each of the two sections of the oven, in which the gaseous fuel is burned, 95 17, 17 indicate the upright flues which communicate at their lower ends with said passages 15, and 18, 18 indicate upright flues which communicate at their lower ends with the passage 16. The upper horizontal flues 100 or passages through which the heated products of combustion pass on their way from the passages 17 to the passages 18, or vice versa, are indicated by 19, 19. Two upright flues 20, 20 lead upwardly from the adjacent 105 ends of the horizontal passages 16, 16. Said flues 20, 20 are separated at their upper ends from the upper horizontal passages 19, 19 and communicate by means of openings 21, 21 with a common horizontal passage 22 110 which extends through the upper wall of the oven to the end of the said upper wall adja-

cent to the receiving end of the oven. Vertically movable valves 23, 23 are employed to control the openings 21, 21. A pipe 24 leads from the discharge end of the passage 22 downwardly to the bottom of the combustion chamber 6, which surrounds the pre-coking chamber 4.

25, 26 indicate the regenerators, which communicate with the passages 15, 16 and with 10 the stack in the usual manner.

In the operation of the apparatus described, assuming that the oven is being heated by fuel burned in the passage 16 of the left-hand section of the oven, and by fuel 15 burned in the passage 15 of the right-hand section of the oven, the valve 23 for the left-hand section of the oven will be opened, while that belonging to the right-hand section of the oven will be closed. The products of combustion arising from the fuel 20 burned in the passage 16 of the left-hand section of the oven, principally pass upwardly through the passages 18, 18 downwardly through the passages 17, and into 25 the passages 15 from which they will pass out through one of the regenerators to the stack. A portion of said heated products of combustion will be diverted through the passage 20 and openings 21, and thence through 30 the passage 22 and pipe 24 to the chamber 6 surrounding the pre-coking passage.

When the right-hand section of the coking chamber is being heated by the combustion of fuel in the passage 16 thereof, which will 35 take place at the time fuel is being burned in the passage 15 of the left hand section of the oven, the valve 23 which belongs to said right hand section of the oven will be open, the valve 23 of the left hand section 40 then being closed, and the heated products of combustion from said right hand section of the oven will then be similarly conveyed through the passage 22 and pipe 24 to the chamber 6.

45 The heated products of combustion delivered to the chamber 6, as above stated, serves to effect the pre-coking or superficial coking of the coal in the pre-coking passage 4, and after said heated products of combustion 50 have passed through said chamber 6 they are delivered through the pipe 10 to the space surrounding the bin 8, to the walls of which heat is transmitted to the coal within said bin to a degree sufficient to heat the 55 coal therein without coking it. After circulating around the walls of said bin 8, said heated products of combustion make their exit from the top of the casing 9 to the stack 14.

60 Fig. 2 indicates, in perspective view, an "Otto Hoffman" oven embracing two rows of coking chambers and provided with feed openings 30, 30, through which fuel is introduced into the said coking chambers. Said 65 coking chambers in the two rows are shown

as arranged end to end and in alinement with each other. Said Fig. 2 illustrates, in section taken through the wall between two adjacent coking chambers, the flues or passages in said wall. Said passages include 70 horizontal, upper passages 31, 31 corresponding with the passages 19, 19 shown in said Fig. 1. From said passages 31, 31 of each pair of coking chambers, passages 32, 32, formed in the top wall of the oven, lead 75 upwardly to and discharge into a longitudinally arranged pipe 33 which extends lengthwise of the oven over the top of the same.

34 indicates, as a whole, a coal supply bin, 80 having a plurality of bin compartments provided with a casing or jacket which form an inclosure surrounding said compartments. With the bottom of said casing is connected the pipe 33 and the top of the same is connected by an exit pipe 35 with a stack 36. The bin compartments open at their lower 85 ends into two discharge spouts 37, 37 arranged in the same vertical plane with the rows of feed openings 30, 30 of the oven.

90 Track rails 38, 38 are laid along the top wall of the oven at the sides of the feed openings, on which track rails run hopper-bottom cars 39, 39. Said cars are adapted to be moved along said rails, so as to bring 95 them over either one of the feed openings and under the discharge spouts 37, 37.

In the operation of the oven thus constructed, heated products of combustion from the heating flues of each of the coking ovens are diverted through the passages 100 32, 32 and, passing through the pipe 33, are discharged into the jacket surrounding the bin compartments and serve to heat the coal therein in the same manner as hereinbefore 105 described. Charges of the heated coal are delivered through the spouts 37, 37 to the cars 39, 39 and by the latter are transferred to the feed openings of those of the coking chambers which it may be desired at any 110 time to fill or charge with coal. The passages 32, 32 are controlled by valves, one of which is indicated by 40, so that connections between the heating flues of one or more of the coking chambers and the pipe 33 may be 115 cut off when desired.

42, 42 indicate the two regenerators belonging to each coking chamber.

In carrying out my process by the use of the apparatus shown in Fig. 2, a portion of 120 the heated products of combustion from the flues of the oven, after the passage of the same along or over the walls of a coking chamber or chambers thereof, is conducted over the walls of the supply bin and utilized 125 to effect preliminary heating of the coal in said bin, without coking of the said coal.

When my invention is carried out in connection with the operation of an "Otto Hoffman" or any other similar form of 130

coke oven provided with regenerators, a portion of the products of combustion may be taken from the flues of the oven at a point between the passages in which combustion of the fuel takes place and the regenerators without requiring the burning of a greater amount of fuel than necessary to effect the coking of the coal. This arises from the well-known fact that, in coke oven practice, 10 a considerable percentage of waste heat is available in excess of that required to heat the maximum amount of regenerator space to the maximum temperature required and utilizable by the incoming air. This condition arises from the relative volume of gas and air employed in the process and also from the fact that the gas is not regenerated. A certain amount of the heated products of combustion may, therefore, be abstracted, 20 after the said products of combustion pass through the main heating flues and before the same reach the regenerator on the way to the stack, without lessening the efficiency of the fuel in the coking operation. The abstracted portions of the products of combustion may be, therefore, utilized to effect the preheating of the coal or to transmit to the charges of coal a non-coking heat, as hereinbefore set forth, without requiring the burning of any, or materially larger, amount of fuel than if no portion of the products of combustion were so abstracted.

I claim as my invention:—

1. The process of coking coal, which consists in introducing the coal into a supply bin, transferring the coal from said supply bin to a coking oven, conducting the heated products of combustion from burning fuel

over the outer surface of the walls of said coking chamber to effect the coking of the coal therein, passing the air fed to the fuel through a regenerator to heat the air, conducting through a regenerator a portion of the said heated products of combustion and transmitting to the walls of the supply bin 45 non-coking heat from another portion of said heated products of combustion to effect preliminary heating of the coal.

2. The process of coking coal, which consists in introducing coal into a supply bin, 50 transferring the coal from said supply bin to a pre-coking passage, advancing the coal through said pre-coking passage into a coking chamber, conducting the heated products of combustion from burning fuel over the 55 outer surfaces of the wall of said coking chamber to effect the coking of the coal therein, passing the air fed to the fuel through a regenerator to heat the air, conducting through a regenerator a portion of 60 the said heated products of combustion, and applying coking heat to the coal in the pre-coking furnace and non-coking heat to the coal in said supply bin, by conducting 65 into contact first with the walls of said pre-coking passage and thereafter with the walls of said supply bin another portion of said heated products of combustion.

In testimony, that I claim the foregoing as my invention I affix my signature in the presence of two witnesses, this 27th day of July A. D. 1908.

SAMUEL B. SHELDON.
